TANK CLOSURE DEVICE

De Lacy F. Ferris, Sepulveda, Calif., assignor to the United States of America as represented by the Secretary of the Army

Filed Dec. 21, 1965, Ser. No. 515,488

4 Claims. (Cl. 220—89)

This invention relates to closure devices and more particularly to a quick-opening, rupturable closure device for the outlet of fuel system tanks.

It is desirable to hermetically seal packaged liquid rocket propellant tanks with a closure device which will resist high pressures during storage and transportation but which will quickly open at low pressures when the tanks are pressurized and the rockets started. Moreover, it is desirable that such a closure device be simple and compact in construction and readily operable from a closed, completely sealed position in the tank outlet to a fully open position therewith.

Prior to the present invention, it has been customary, when the fuel tank is to be stored or transported, to locate a closure device including a wall-to-wall shearable burst diaphragm of thin sheet metal within or across the tank outlet, the diaphragm being scored or coined circumferentially and supported by a support element which extends across the tank outlet from one side thereof to the other. Thus, when it is desired to utilize the stored liquid fuel, the diaphragm must initially be unsupported so as to allow the same to be ruptured along its score pattern. In this prior arrangement, in order to unsupport the burst diaphragm, it is necessary that the supporting element be moved a distance greater than the diameter of the tank outlet and the score pattern. In this type prior structure, a relatively large support element is required since said element bridges the entire diameter of the tank outlet and, in addition, carries load as a beam. This arrangement has the further disadvantage of taking up considerable space axially, thus, reducing the effective axial length of the tank.

Accordingly, with the foregoing in mind, it is the primary object of the present invention to provide a closure device for the outlet passage of a fluid propellant tank which is highly effective for sealing the tank against high pressures but capable of rapidly opening the passage to flow when desired.

Another object of this invention is to provide a closure device which may be activated between closed and open positions by remote control means.

A further object of the invention is to provide a tank closure device which is relatively small or short in axial length so as to allow the effective axial length of the tank to be relatively longer.

A still further object of the invention is to provide a tank closure device utilizing a rupturable diaphragm which device prevents ruptured pieces from going downstream.

An important feature of the invention resides in the provision of a burst diaphragm type, hermetic sealing element disposed in the flow passage and formed with score marks which may be ruptured at the instant the closure is opened or at a predetermined time thereafter.

Another feature of the present invention resides in the provision in a closure device of a burst diaphragm having a supporting arrangement which is subject to shear rather than compressive loads.

Further objects, features and advantages of this invention will be apparent from the following detailed description and the accompanying drawing, wherein:

FIGURE 1 is a plan view of a tank closure device constructed in accordance with the present invention and disposed in closed, hermetically sealed position within a

2

fuel tank outlet, this view being taken in a direction as viewed from outside the tank looking inwardly;

FIGURE 2 is a sectional view taken substantially on line 2—2 of FIGURE 1; and

FIGURE 3 is a sectional view taken on line 3—3 in FIGURE 1.

Referring now in detail to the drawing, wherein like reference numerals designate corresponding parts in the several views, reference numeral 10 designates a cylindrical outlet body of a fuel tank or the like fluid vessel (not shown), which body defines a cylindrical flow passageway 12. The direction of flow from tank outlet 12 is indicated (FIGURE 2) by the directional arrow in the downstream area thereof. Referring to FIGURE 1, cylindrical body 10 is formed with a substantially annular support shoulder 14 extending radially inwardly from the inner cylindrical surface defining flow passageway 12.

To completely close and hermetically seal the outlet passage against flow outwardly thereof during storage and transport conditions a rupturable, hermetic sealing sheet or burst diaphragm 24 is disposed across the cylindrical flow passage. Burst diaphragm 24, which is preferably formed of thin sheet metal, is secured as by welding about peripheral portion 26 thereof to the inner, cylindrical wall of the tubular tank outlet body at a position upstream of shoulder 14 (FIGURE 2). The upstream side (tank side) of burst diaphragm 24 is locally weakened by scoring or coining. Score marks are indicated (FIGURES 1 and 3) by reference numeral 28.

In order to support the scored burst diaphragm during storage and transportation of the propellant tanks (not shown) and thus, to prevent the same from rupturing unintentionally, a supporting assembly designated generally by reference numeral 30 (FIGURE 2) is provided on the downstream side of the diaphragm. Supporting assembly 30 comprises a plurality of generally triangular or wedge-shaped, auxiliary beams or plates 32, a single, wedge-shaped, main beam or plate 42, and an actuating rod 50. Each auxiliary plate 32 has a pair of side edges

40 forming an apex at the radially inner end thereof (FIGURE 1). Each of the support plates is secured, preferably as by spot-brazing at 33 (FIGURE 1), to the downstream side of the diaphragm. The radially outer end portion 38 of each auxiliary plate rests for support on annular shoulder 14. Main plate 42 is supported at outer end or base portion 44 on annular shoulder 14. The main support plate is recessed (FIGURE 3) along each of its side edges to form a pair of elongated ledges 46, which face upstream toward the tank. Thus, one of the side edges, designated 31, of each of the auxiliary plates rests for support on a ledge 46 (FIGURES 1, 3). Actuating rod 50 is slidably disposed in bore 18 of protrusion 16 and is provided on its inner end with a recessed portion defining a ledge 52 for supporting the other end portion 45 of the main plate. To guide actuating rod 50, a guide pin 62 is positioned in a bore 64 which extends normal to bore 18. The upper end of the guide pin is received in guide groove or slot 54 formed in the downstream side of the inner end of the actuating rod. The outer end of the rod is provided with an aperture 60 whereby the same may be connected with any convenient actuating means or remote control means.

To assemble the closure device within body 10, burst diaphragm 24 is secured as by welding about its outer peripheral portion 26 to the inner wall of said body. Support plates 32 and 42 are secured to the downstream side of said diaphragm as by spot-brazing as indicated at 33 (FIG. 1). Each auxiliary support plate 32 is supported at one end on shoulder 14 and at the other end on a respective ledge 46 of main support plate 42 (FIGURES 1 and 3) while main support plate 42 has one end 44 resting on shoulder 14 and the opposite apex end

65

45 thereof resting for support on ledge 52 provided on the inner end of actuating rod 50 (FIGURE 2). Thus, with the closure device secured within the flow passageway in the manner described and illustrated, the propellant tank, or like pressure container, is completely closed and hermetically sealed to thereby resist high pressures developed during storage and transportation. It is noted that, in the storage and transport position, substantially 10 the entire area of the burst diaphragm is supported by the support plates. Particular note is made that substantially all the area weakened by score marks or score pattern 28 is effectively supported by said support plates.

When it is desired to transfer fuel, or the like fluid, through the outlet flow passage, the closure device may be rapidly moved from the above described closed, or 15 storage and transport, position to open position. Thus, actuating rod 50 is slidably moved outwardly of its bore, i.e., in a direction radially outwardly from the axis of the tubular body so as to move ledge 52 clear of apex end 45 of the main support plate to unsupport the same. 20 The tank is simultaneously pressurized upstream of the closure device. Accordingly, with release of support ledge 52 from supporting engagement with support plate 42 and upon application of pressure upstream of the diaphragm, the latter is caused to rupture abruptly along the score marks. Since each of the support plates is spot-brazed to a segment of the diaphragm between adjacent score marks, the same will remain secured thereto when rapidly thrown downstream against the inner walls of the outlet flow passage thereby allowing substantially free flow of fuel from the outlet passage through the ruptured diaphragm.

While the foregoing describes the burst diaphragm as being ruptured simultaneously with application of increased pressure to the fuel tank and withdrawal of the actuating rod, it should be apparent that the diaphragm and its score pattern could be designed so that rupture of the diaphragm may be effected by application of pressure at a predetermined time after withdrawal of the actuating rod. Moreover, while the closure device is described herein as positioned within a tank outlet, it should be understood that the device is adapted for use with other flow passages and the device could as well be formed as a separable attachment unit for securement at its upstream end to the opening of a tank outlet or the like flow passage.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A closure device for closing the cylindrical passageway of a tubular tank outlet body having an inner end and an outer end and provided intermediate said ends with a substantially annular shoulder projecting radially inwardly from its internal wall and a protrusion extend-

ing radially outwardly from its external wall, said protrusion having an axial, through bore opening at its radially inner end into said passageway, said device comprising:

- 5 (a) a disc-like burst diaphragm made of thin, sheet metal and secured about its peripheral edge portion to said internal wall at a position between said shoulder and said inner end for hermetically sealing said passageway against flow outwardly thereof, said diaphragm being formed with a plurality of substantially radially extending score marks in the axially inwardly facing surface thereof; and
- (b) means for supporting the burst diaphragm including a plurality of support plates secured to said diaphragm on the opposite, outer surface thereof and substantially covering said score marks and an actuating rod slidably received in said bore in the protrusion, said rod having ledge means formed on its radially inner end and connecting means formed on its outer end, said support plates being supported at the radially outer ends thereof by said annular shoulder and at the opposite inner ends by said ledge means thereby to normally provide rigid support for said scored diaphragm, said actuating rod being adapted to be moved in a direction radially outwardly to a position so as to unsupport said plates at the inner ends thereof allowing said burst diaphragm to be ruptured along said score marks upon application of pressure on the inner side of said diaphragm.

30 2. A closure device as defined in claim 1 wherein said plurality of support plates include a single, main plate extending diametrically across the central portion of said diaphragm and having one of its ends supported on said annular shoulder and the opposite end thereof supported on said actuating rod ledge, and a plurality of smaller, 35 auxiliary plates, each said auxiliary plate having one end supported on said annular shoulder and the opposite end supported directly by said main plate.

35 3. A closure device as defined in claim 2, wherein each of the support plates is substantially triangular in shape with the base of each plate being supported on said annular shoulder, and wherein each said auxiliary plate is disposed in such manner that each of the two sides excluding the base thereof extends in substantial alignment with a score mark.

40 4. A closure device as defined in claim 3, wherein said score marks extend substantially radially of the diaphragm so as to divide the latter into a plurality of distinct, triangular segments and wherein each of said score marks extends radially to a point short of the outer 45 peripheral portion of the diaphragm whereby said segments are swung in an arcuate path from its sealed position to a position adjacent the inner wall of said body when the diaphragm is ruptured.
